LIGHT COLLECTING FRONT SIGHT FOR FIREARMS

John T. Dickinson, Seattle, Wash.

Application January 16, 1950, Serial No. 138,899

2 Claims. (Cl. 33—47)

1

This present invention is drawn to a front sight for fire arms in which the upstanding portion of the sight that is normally viewed in silhouette against the target is formed of acrylic resin of the type whose light conducting properties are well known. In forming a sight from this material rather extensive side areas are presented for the collection of light, and in use this light is conducted to the rear edge of the sight, which is that portion viewed by the shooter when the fire arm is in use. When so arranged, the maximum intensity is given to the light on the rear edge of the sight making it particularly adaptable for use when light is poor, as in twilight or at dusk.

Ever since the creation of rifled arms particularly, mankind has been endeavoring to produce a front sight for such weapons that would make it possible to more effectively use the fire arm for accurately aimed fire when general conditions are such that the light intensity is of a low order. This condition occurs in early morning shooting and shooting towards evening. Many attempts have been made in the past to produce such a sight, the earliest known examples probably were to use ivory, because it was white. Other sights have been produced in which sulphurous compounds were used, so that the phosphorescent glow, which could be obtained from the old sulphur match tended to give an outstanding appearance to the front sight. The next recognized development was in the use of the so-called gold bead sights, wherein a high copper alloy was usually employed which could be burnished to give the appearance of gold. Although in some of our early fire arms, particularly dueling pistols, we find that actual gold was employed for this purpose, this was not a common practice.

These various sights were some improvement over the plain dark metal front sights, especially the bead sights, which, in effect, reflected light themselves. Riflemen soon determined, however, that the very fact that these sights reflected light worked to the disadvantage of the rifleman in endeavoring to get accurate aim fire. The reflection from the front sight would, in effect, change its position on the sight with varying changes of the light source. Consequently an actual error was introduced in sights. Military riflemen have long been aware of this condition and for the sake of accuracy, have blackened their front sights, as with camphor or acetylene smoke, and while they improved the accuracy of the sighting, they went backward in collecting light, in their endeavor to make it

2

possible to use their weapon under adverse conditions. Many steps have been made to provide special illumination for the front sight. This has been achieved by having, what might be termed a sky-light, cut in a hood which fitted over the front sight. In this way top light was directed on the aiming portion of the sight, and the same remained substantially constant. Another attempt at the same problem has been to employ reflective surfaces, which, in effect, were small mirrors so pitched as to illuminate the margin of a sight visible to a shooter. All of these various arrangements have been found to improve conditions for the shooter under certain conditions only. They were not all-around sights, which could be used under conditions as the shooter found them. The sights of this present invention, however, are believed to fully satisfy the shooters' particular problems, and in distinction from the elaborate arrangements, many times offered in the past, this present invention solves the problem in a very simple manner.

The principal object of this invention therefore is to provide a front sight for firearms which will have the faculty of collecting light impinging on its lateral surfaces and this light or at least a very substantial part of it is conducted to that surface which is facing the shooter and which he uses as the silhouette of the front sight.

30 A further object of this present invention is to provide a light collecting front sight for fire arms which is very economically constructed, which does not involve complicated accessory structures, and which can, by the same token, be very economically produced.

35 A further object of this invention is to provide a light collecting front sight which is adaptable to all the various forms of mounting, which are incidental to the adaption of front sights to our various forms of firearms.

40 Further objects, advantages and capabilities will be apparent from the description and disclosure in the drawings, or may be comprehended or are inherent in the device.

45 In the drawings:

Figure 1 is a perspective view showing a gun sight for use on the muzzle end of a firearm and showing the usual dovetailed mounting arrangement so commonly used on rifles especially;

50 Figure 2 is a perspective view showing a semi-bead type of sight and the form employed for use in certain types of hand guns, as revolvers and pistols;

55 Figure 3 is a view in perspective showing a form of front sight of the type wherein the sight portion is readily removable from a mounting

block. This form of sight is normally employed on target rifles;

Figure 4 is a perspective view showing the sight as adapted for use on shotguns;

Figure 5 is a perspective view showing a blade type of front sight which has general application in various forms of rifle firearms. It employs a full length through bead, and is a form of sight quite generally employed on hunting rifles;

Figure 6 is a perspective view showing a protective guard and reflector for use on my sight.

Referring more particularly to the disclosure in the drawings, the numeral 10 designates the body portion of this new sight. It consists essentially of a sheet of light conducting plastic material, of which acrylic resin is an example, that is transparent, normally, although certain of its desirable properties may be retained even though the material may be translucent. The highest degree of light transmission, however, is obtained in the transparent materials, which are preferably colored. It is conceivable that for various types of background that the color of sight could be varied so as to provide a distinct contrast. Experience has shown, however, that red is probably the most advantageous color as red occurs only seasonally, normally, in nature. Consequently, a front sight that appears red when viewed from the shooting position will give a marked degree of contrast against the greatest number of targets and backgrounds.

The choice of color is of considerable importance. As items are viewed, some colors that look fresh on bright days look faded or dull on cloudy days. This variation in the spectrum of daylight takes place in going from the open into the shade, as in hunting, when one goes from the open areas into the brush or into the dense forest. In the dense forest, the light appears greenish owing to the scarcity of the yellow rays, hence any substance in which red and yellow predominate appears black, and makes no contrast with black metal, such as is used in so many front sights. Most substances available for construction of gunsights do not themselves produce light. They merely have the appearance of color from their ability to reflect light; and if the light available for their reflection is of some characteristic hue, due to the effect of local foliage on the light, for instance, it tends to reflect that color, and therefore is not in sharp contrast when used under those conditions. This sight, if made in clear plastic, would be guilty of the same fault. However, when an appropriate dye is used in the material to give it a definite color, that color will predominate and, as far as the user is concerned, it is that color.

The exact form of body 10 will, of necessity, need to be varied in order to accommodate this principle to the various forms of front sights now used on firearms. In the accompanying drawings six different forms are shown which are very representative of the wide range of designs, which must be supplied in order to make this front sight adaptable to the various forms of firearms to which it can be effectively fitted. In keeping with the experience obtained with various forms of ivory, copper alloy, brass, and silver blade sights, it has been found desirable to employ, preferably, a steel mounting unit as is common with so many of the other forms of front sights in order that a durable, shock-resisting form of sight can be supplied to the shooter. It will be understood, it is believed, that the blade form generally shown might be modified by swelling

the dovetail portion 11 of Figures 1 and 4 to give the general proportions of portions 10 and 14 of Figure 1 and thus increase the surface available for collecting light.

In referring to the drawings, it will be noted that Figures 2 and 5 show blade type sights. These are for use as replacements in those sight structures that are built up out of metal to accept a blade type sight which may be of any desired form. Normally, bead sights are predominantly used in hunting and the flat top sight normally used in target shooting. However, the mount for these sights comes approximately half way up on the sides of the same and gives a large degree of support and protection to the sight. The sight in Figure 1, which is probably the more commonly used on rifles, employs a dovetail male portion 12, which is adapted to fit into a corresponding dovetailed slot in the muzzle end of the gun. It will then be noted that the sides, formed of the same metal as 14, extend only part way up on the body 10 of the sight. This gives relatively large side areas exposed so that light can be picked up and then passed through the resin or plastic material and provides a high degree of illumination to the edge portion 16, which faces the shooter and which, in effect, becomes that portion of sight he sees when aiming. In this form of sight it has been found convenient to use a surface reflector at 18 so that any light that will pass down through body 10 will be reflected back up from reflector 18 and add to the volume of light available on surface 16.

In the bracketed view of Figure 3 unusual pains have been taken to fully protect body 10 of the sight from damage. This has been achieved by providing the parallel disposed ribs as 20 and 21, one on each side of the sight, so that in case the arm is dropped or is bumped against some object, the ribs 20 and 21 can be expected to take the shock. This arrangement is not new in principle, in that it has long been employed on military rifles of foreign manufacture and, in recent years, on our own service rifles in this country, as the Garand and carbine M1, an outstanding example being in the Enfield rifle, the model 1917 in which the side members extend considerably above the front sight blade. In the view of Figure 3 a detachable sight is shown, in which a dovetailed slot is provided at 23, which is adapted to engage a base block 24, which is secured to the muzzle of the gun by a plurality of screws as 26. A locking screw 28 is provided to secure the sight base 30 in fixed relationship to block 24 when in use, yet providing for the easy detachment of sight base 30, particularly when it is desired to use an alternate telescope sight on the rifle. In this form of sight to provide, on the one hand, for the easy mounting of body 10, and to further provide a convenient way of employing a reflector for the bottom edge of body 10, there is provided a secondary mounting member 32 which fits, preferably, into a dovetailed slot in base 30, as it is believed it will be readily understood, by viewing Figure 3, so that the sight body 10 can be conveniently changed if, for instance, a different form of sighting member or a different color is desired. At the same time an effective reflecting surface can be provided at 34. By forming the inner walls of ribs 20 and 21 as curved or beveled surfaces at 36 and 37, very efficient reflecting means is provided for directing additional light on to blade 10. These curved surfaces, 36 and 37, have their center of generation substantially on the vertical plane of sight

blade 10. Small transverse ribs or other means may be formed on surfaces 36 and 37 to prevent the reflecting surfaces from directing any light back to the shooter's position.

In Figure 4 has been illustrated the muzzle of a shotgun. Here, due to the thin wall of the gun barrel 40, it has been found desirable to provide a relatively thin metal band 42, which is given a U-shaped form at 44 which will accept a body 10 having a beveled bottom section 11. This form is believed to be well illustrated in Figure 4; and again, a convenient means is provided for the changing of the plastic sight member 10, and the metal forming portion 44 can be finished to give it reflective properties to further the effective use of this form of sight arrangement.

In Figure 6 a typical sight base 54 is shown which may be taken as representative of any desired type of base. The sight, 10, of light transmitting material, is secured to said base and a protective shield 58 disposed to protect the sight from damage from all directions. The shield is slotted at 59 and thus is disposed on each side of the sight. The shield then should be formed to fend off any damage from the sight and be firmly secured to the base as by having its ends inserted in slots 60 and 62 of the sight base 54. The various surfaces of shield 58 may be finished to provide reflective surfaces to direct light into sight 56.

The exact shape of the plastic light-transmitting material which forms the blade portion of this sight may conform in shape to any of the standard forms of front sights. Figures 1, 3, and 4 show blade type of sights, either with a vertical face facing the shooter, or with a curved or inclined face after the showing of Figure 1. Any other form of sight may be made of this material. The top line of the sight, as 46 may be so sloped that the margin closest to the shooter may be higher if that form of sight is desired. Similarly, the various forms of under-cut or overhanding sight blades can be formed if desired. In Figures 2 and 5, two forms of bead sights have been shown; one, in Figure 2, the semi-bead in which a bead-like form is shown in outline at 48, which merges into the thinner portion of the sight blade at 50, and second, the full bead form, wherein the side facing the shooter is desired to be semi-spherical. This may be arranged as at 52 in Figure 5, and the size of the bead can be maintained throughout the length of the sight, after the showing of the figure. The opening shown in Figure 5 and the circular opening, elongated opening and slot shown in Figure 2 are typical of the various openings formed in usual sight blades to correspond to clamp means on muzzles of various types of rifles. From this large variety of illustrated forms, it is believed it will be evident that any of the accepted styles of sights can be made to embody the principles of this invention.

Throughout this description reference has been made to acrylic resins as most desirable. This is due to the fact that these resins have a

high light transmission factor, normally between 88 and 92 per cent, and their ability to "pipe" light is well proven. These plastics form an excellent base for fluorescent materials and under certain conditions of use are very effective as gun sight materials. The choice of plastic materials for gun sights is not limited to acrylics as the following may also be used: cellulose acetate and butyrate, cellulose nitrate, ethyl cellulose, polystyrene and the vinyls all have light transmission properties which can be used to advantage. No doubt other plastics will be developed which will lend themselves to this use.

It is believed that it will be clearly apparent from the above description and the disclosure in the drawings that the invention comprehends a novel construction of a light collecting front sight for fire arms.

Having thus disclosed the invention, I claim:

1. In a front sight for fire arms, the improvement, comprising: a member forming a blade of the sight formed of material having the property of high transmission of light; said blade member being colored to contrast with the color of the foliage; a reflecting member positioned in intimate contact throughout the entire bottom edge of said blade member to reflect light passing from said blade member back into the same; and a guard member disposed at either side of said blade member to guard the same, said guard members being formed as curved surfaces with their center of generation substantially on the vertical plane of said sight blade.

2. In a front sight for fire arms, the improvement, comprising: a blade member forming the upstanding portion of the sight, the material forming said member being of the type having the property of high transmission of light; a secondary mounting member enclosing the bottom margin of said blade and providing a reflective means for reflecting light back into said blade; and a protective shield for said blade member having a central slot in which said secondary member is positioned, and said protective shield having inwardly curved reflective surfaces, for reflecting light into said blade member, extending from a point near the forward base of said blade member to a point at the rear of said blade member.

JOHN T. DICKINSON.
